(57) **CLAIM**

The ornamental design for an exercise bike, as shown and described.

DESCRIPTION

FIG. 1 is a perspective view of an exercise bike showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is an enlarged detail view of area 8 shown in FIG. 1.

FIG. 9 is an enlarged detail view of area 9 shown in FIG. 1.

FIG. 10 is an enlarged detail view of area 10 shown in FIG. 1.

FIG. 11 is an enlarged detail view of area 11 shown in FIG. 3.

FIG. 12 is an enlarged detail view of area 12 shown in FIG. 3.

FIG. 13 is an enlarged detail view of area 13 shown in FIG. 5.

FIG. 14 is an enlarged detail view of area 14 shown in FIG. 6.

FIG. 15 is an enlarged detail view of area 15 shown in FIG. 6; and,

FIG. 16 is an enlarged detail view of area 16 shown in FIG. 6.

1 Claim, 16 Drawing Sheets
